2,329,850

PIPE TONG

Joseph A. Peterson and Carl E. Olsen,
Houston, Tex.

Application November 16, 1940, Serial No. 365,918

9 Claims. (Cl. 81—91)

The invention relates to a pipe tong of the type used in making up and breaking down pipe connections.

The general arrangement of the structure, jaws, handle and locking device of the present disclosure is the same as that set out in the patent to J. A. Peterson and Carl E. Olsen, 1,857,397 issued May 10, 1932. The present improvement, however, embodies an attachment for the tong wherein the jaws will be extended or moved to open position so that they may be more readily passed about a pipe.

In the previous patent the jaws were normally held retracted by a spring, and it was found that considerable wear on the teeth of the tong resulted in forcing the jaws about a pipe. The present improvement therefore contemplates that the jaws may be extended by the operator just prior to being passed about the pipe and in this manner the use of the tong will be facilitated and it can then be locked in position about the pipe as disclosed and contemplated in said prior patent.

It is one of the objects of the invention to provide a pipe tong with a mechanism for extending the jaws to be passed about the pipe.

Another object of the invention is to provide a pipe tong with a combination locking and extending device which will extend the jaws when moved to one position and lock them in place when moved to another position.

Other and further objects of the invention will be readily apparent when the following description is considered in connection with the accompanying drawings wherein:

Fig. 1 is a side elevation of the tong with part of the handle broken away to show the arrangement of the jaws and the operating mechanism.

Fig. 2 is a view similar to Fig. 1 except the jaws are shown as being extended by the mechanism preparatory to being passed about a pipe.

Fig. 3 is a bottom edge view of the tong.

Fig. 4 is a section taken on the line 4—4 of Fig. 1.

Fig. 5 is a broken detailed arrangement of the extending finger.

Fig. 6 is an enlarged view of the combination locking and extending lever.

Fig. 7 is a section taken on the line 7—7 of Fig. 6.

Fig. 8 is a side elevation of the entire tong with the jaws in extended position.

In Figs. 1 and 8 the tong is shown generally and embodies a handle 2 having an enlarged head 3 which is provided with the forked por-

tions 4 and 5. This head as seen in Fig. 3 is bifurcated so as to provide the side portions 7 and 8 which are spaced apart.

Each of the forked portions carries a pivot pin 9 upon which the jaws 11 and 12 are pivoted respectively. The jaw 11 as seen in Fig. 1 is arranged for pivoting movement with the heel portion 13 disposed in a recess between the sides 7 and 8.

10 The jaw 12 has a slot 16 therein which is arranged to receive the pin 9. In order that the jaws may have sliding movement relative to the pin, a bearing block 17 is arranged about the pin 9 and the jaw may slide on this block. The jaw 12 has a recess 18 therein from which the spring 19 projects so as to bear against the block 17.

A guide rod 20 is disposed within the spring. One end of the spring bears against the base of the recess 18 and normally tends to force the jaw to the right, as seen in Fig. 1. This jaw 12 has a head 22 thereon which is arranged to fit in a socket 23 in the heel 13 of the jaw 11 so that the jaws are coupled together but are permitted relative pivoting and sliding movement.

25 The jaw 11 has a curved face 25 which carries a tooth 26 which is arranged to have the corner 27 thereof projecting beyond the face 25 so as to cut into the surface of the pipe and retain an engagement therewith. It should be noted that the opening 28 which receives the square tooth 26 has a rounded base which in turn receives a half round key 29 which can be driven in behind the key to firmly hold the key in place when the ends thereof are bent over.

30 The jaw 12 has a recess 30 which carries spaced keys 26 so that there will be a three-point contact with the pipe.

Each of the side pieces 7 and 8 have a lug 33 projecting therefrom and a pivot pin 34 is passed therethrough. Pivoted on this pin is the combination locking and extending lever 35. The end 36 of this lever is arranged to be engaged by the operator and may be depressed into the recess 37 provided in the handle as seen in Fig. 1, or it may be pivoted in a clockwise direction until the end 36 engages the back portion 38 of the jaw 12.

35 This lever 35 has a cam portion 40 thereon which is arranged to move closely against the surface 41 on the end 13 of the jaw 11. These parts are so constructed and arranged that when the cam 40 engages the portion 41 of the jaw 11 that then the heel 13 of the jaw can not move in a clockwise direction. This, of course, prevents the jaw portion 11 from pivoting and locks

both of the jaws together so that the tong will be firmly locked about the pipe.

Fig. 5 shows a finger 45 which is pivoted about the pin 34 and has a lug portion 46 thereon which is arranged to engage a shoulder 47 provided on the side lever 35. In this manner, as the lever 35 is pressed from the position of Fig. 1 into the recess 37, the shoulder 47 will move in a counter-clockwise direction so as to move the finger portion 48 against the head 22 of the jaw 12. In this manner the head will be moved in the direction of the arrow shown in Fig. 5 so as to extend both of the jaws as seen in Fig. 2. The spring 19 helps to retract the jaws, and the pressure on the lever 35 to work the finger 45, must overcome the force of this spring.

A flat spring washer 50 may be disposed about the pin 34 and between the lug 33 and the lever 35 and held in place by the spring 43 of Fig. 6. A rivet 51 in the lug 33 bears against such washer and the washer has a recess 52 therein to fit over the rivet and thus hold the lever in locked position. The prong 53 punched out of the recess 52 serves to clinch the washer 50 to the lever as best seen in Fig. 1.

In operation the lever 35 may be depressed as seen in Fig. 2 to extend the jaws and the tong passed about the pipe. The lever is then released so that the jaws move to retracted position and if the lever is then pivoted over the position shown in Fig. 1 in a clockwise direction the cam 40 will engage the heel portion 41 of the jaw 11 and lock both of the portions in position about the pipe.

Broadly, the invention contemplates an attachment for a pipe tong by which the position may be extended.

What is claimed is:

1. A pipe tong including a handle, a pair of jaws each pivoted thereon, means to normally hold said jaws retracted, additional means to extend said jaws including a lever to overcome said first means, and means on said lever to also lock said jaws in retracted position.

2. In a pipe tong having a handle and a pair of jaws each pivoted on said handle, a lever to lock said jaws in pipe engaging position, and means operable by said lever when not in locking position to extend the jaws to be passed about a pipe.

3. A tong having a handle, a jaw pivotally mounted on said handle, a jaw pivotally and slidably mounted on said handle, a locking member to positively move said jaws together and

prevent opening of said jaws, and means also operable by said member to move said jaws to open position.

4. A tong having a handle, a jaw pivotally mounted on said handle, a jaw pivotally and slidably mounted on said handle, a locking member to positively move said jaws together and prevent opening of said jaws, and means also operable by said member to move said jaws to open position when said member is moved away from the locking position.

5. A tong having a handle, a jaw pivotally mounted on said handle, a jaw pivotally and slidably mounted on said handle, a locking member to positively move said jaws together and prevent opening of said jaws, and means also operable by said member to move said jaws to open position, said last means including a finger piece.

6. A tong having a handle, a jaw pivotally mounted on said handle, a jaw pivotally and slidably mounted on said handle, a locking member to positively move said jaws together and prevent opening of said jaws, and means also operable by said member to move said jaws to open position, said last means including a finger piece to be moved by said member.

7. A tong having a handle, a jaw pivotally mounted on said handle, a jaw pivotally and slidably mounted on said handle, a locking member to positively move said jaws together and prevent opening of said jaws, and means also operable by said member to move said jaws to open position, said last means including a finger piece to be moved by said member and having projecting portions thereon to engage said member and one of said jaws.

8. In a pipe tong having jaws, a handle, means to pivot each of said jaws to said handle and to each other, a finger on said handle, means on said finger to engage one of said jaws, and a lever to move said finger to extend said jaws from a normally closed position to be passed about an object.

9. A pipe tong including a handle, a pair of jaws each movable thereon, means to normally hold said jaws retracted, additional means to extend said jaws including a lever to contact one jaw and to overcome said first means, means on said lever to also lock said jaws in retracted position, and additional means to latch said lever in locking position.

JOSEPH A. PETERSON.
